ANTITANK AMMUNITION

Jan V. Weinberger, Truro, Nova Scotia, Canada

Application October 9, 1944, Serial No. 557,746
In Canada January 26, 1944

1 Claim. (Cl. 102—38)

This invention relates to improvements in anti-tank shells and has for its object to increase the velocity and penetration power of the projectile which is propelled from the shell casing by explosion of the main explosive charge contained in said casing.

The stated object of this invention is achieved by accelerating the combustion of the main charge so that, at the moment of explosion, the pressure developed within the casing of the shell is much higher than in the case of an ordinary shell and therefore exerts a proportionately greater propelling pressure against the projectile. The desired accelerated combustion of the main explosive charge is achieved by appropriate double ignition of the charge as will now be more fully explained with the aid of the accompanying drawings, in which:

Figure 1 is a longitudinal sectional view of an anti-tank shell embodying my invention.

Figure 2 is a transverse sectional view taken substantially along the line 2—2 of Figure 1; and

Figure 3 is a transverse section taken substantially along the line 3—3 of Figure 1.

Referring more particularly to the drawing, 5 and 6 designate, respectively, the main casing and projectile elements of my improved shell. The bottom casing wall 7 is provided with a recess 8 containing a primer or detonator 9. Recess 8 communicates with the interior of casing 5 through a suitable opening 10 provided in the casing wall 7.

A sleeve 11 is arranged in casing 5 adjacent to the projectile 6, said sleeve being held in place by arms 12 and 13, which are attached to the shell casing by soldering, threading, interlocking or similar means of attachment and which also serve to space the upper end of the sleeve from the base of the projectile. Sleeve 11 is open at its lower end and is closed at its upper end except for a small opening 14 which places the interior of the sleeve in communication with the space reserved between the upper end of the sleeve and the projectile. Sleeve 11 contains a second primer or detonator 15 and also serves as a guide tube for the enlarged free end 16 of a firing pin 17, the opposite end of said pin being fas-

tened to a plate 18 provided with two pins 19 which are normally engaged with the bottom casing wall 7.

Casing 5 contains the usual main explosive charge 20. When the primer or detonator 9 is detonated in the usual manner, the detonated charge passes through opening 10 and ignites the adjacent portion of the main charge 20. At the same time the firing pin 17 is thrown against 10 and detonates the second primer or detonator 15, the detonated charge of which passes through opening 14 and effects a second ignition of the main charge 20 adjacent the base of projectile 6. This double ignition of the main explosive charge accelerates its combustion and results in the creation of an exceptionally high pressure in casing 5 at the moment of explosion.

Having thus described what I now consider to be the preferred embodiment of my invention, it will be understood that various modifications thereof may be resorted to within the scope and spirit of the invention as defined by the appended claim.

I claim:

23 A shell comprising a casing containing a projectile-propelling explosive charge, a projectile fitted in and closing an opening at one end of the shell, a detonator carried by the end of the shell remote from said projectile and adapted to be detonated in the usual manner to effect ignition of the charge at a point within the casing adjacent said detonator, a firing-pin guide sleeve arranged in said casing adjacent the inner end of the projectile, a second detonator arranged 30 within said guide sleeve, a movable firing pin having one end fitted in said sleeve and provided, at the opposite end, with a plate having projections normally engaging the end wall of the casing which carries the first mentioned detonator, the arrangement being such that the pressure 35 created by detonation of the firstmentioned detonator acts against said plate and causes the firing pin to be thrown against the second detonator which is thereby detonated to effect a second ignition 40 of the explosion charge at a point within the casing adjacent the inner end of the projectile.

JAN V. WEINBERGER.
